UNITED STATES PATENT OFFICE.

GUSTAF DALÉN, OF STOCKHOLM, SWEDEN.

ELASTIC-FLUID TURBINE.

No. 872,055.

Specification of Letters Patent.

Patented Nov. 26, 1907.

Application filed April 27, 1907. Serial No. 370,688.

To all whom it may concern:

Be it known that I, GUSTAF DALÉN, engineer, a citizen of Sweden, residing at Stockholm, Sweden, have invented a certain new 5 and useful Improvement in Elastic-Fluid 10 Turbines, of which the following is a specification.

The present invention refers to an improvement in elastic fluid turbines of the radial flow type.

Figure 1 shows the turbine in longitudinal section and Fig. 2 in transverse section on the line $x-x$ in Fig. 1.

On the turbine shaft 1 is mounted a turbine wheel 2; provided with a number of concentric rows of buckets 3, between which concentric rows of guide blades 4 on the stationary intermediate portion 5 project. On the other side of said intermediate portion 20 5 a second wheel 6 is mounted on the shaft 1. Said wheel 6 may be provided with concentric rows of buckets 7, between which concentric rows of guide blades 8 on the stationary portion 5 project in the same manner as concerning the wheel 2. Or 7 and 8 25 may indicate concentric rows of tightening rings, fixed on the wheel 6 and the stationary portion 5.

9 indicates the fluid inlet pipe, opening 30 into a central chamber 10 of the intermediate portion 5, said chamber communicating through openings 11 and 12 with the spaces between the wheels 2 and 6 and the stationary portion 5, 13, 14, 15 and 16 indicate concentric chambers formed in the intermediate portion 5, each communicating through 35 openings 17, 18, 19, 20; 21, 22, 23, 24 with said spaces between the wheels 2 and 6 and the intermediate portion 5 in equal radial 40 distances from the shaft 1.

25 indicates the turbine casing, 26 the shaft bearings and 27 the exhaust.

Fluid, for instance steam, admitted through 45 pipe 9 and flowing between the rows of turbine buckets 3 and guide blades 4, will exert an axial thrust in the direction to the left on the wheel 2, said thrust decreasing from the center to the periphery of the wheel in the same degree as the pressure of the motive 50 fluid decreases through the expansion of the same. In the same manner the steam flowing between the rows of buckets and guide blades (or tightening rings) 7 and 8 will exert an axial thrust in the direction to the 55 right on the wheel 6, said thrust also decreasing from the center to the periphery of

said wheel. As now the openings 17-20 open axially opposite the openings 21-24, an equal steam pressure is established in the openings 17 and 21, 18 and 22, 19 and 23, 20 and 24, whereby the two wheels 2 and 6 are completely balanced.

Pipes 28, 29, 30, 31, through which live steam can be admitted to each of the chambers 13, 14, 15, 16, are provided as shown in Fig. 2 for regulating the amount of power delivered by the turbine.

By admitting live steam to a chamber nearer the periphery steam is introduced to buckets and guide blades with a larger area 70 and thus a larger amount of power is produced than if steam is introduced to a chamber nearer the center, as may be fully understood without further description. The admission of steam through the pipes can be 75 regulated by hand or by means of a centrifugal regulator in any manner previously well known.

I claim:

1. In elastic fluid turbines of the radial flow type a stationary intermediate portion, a turbine wheel provided with concentric rows of buckets coöperating with concentric rows of guide blades on the one side of the intermediate portion, a wheel provided with concentric rows of tightening rings, coöperating with concentric rows of tightening rings on the opposite side of the intermediate portion, and steam admitting ports in said intermediate portion. 90

2. In elastic fluid turbines of the radial flow type a stationary intermediate portion between two rotating wheels, fluid admitting ports in said intermediate portion, and openings in said intermediate portion, establishing communication between the spaces between the wheels and the intermediate portion at equal radial distances from the turbine shaft. 95

3. In elastic fluid turbines of the radial flow type a stationary intermediate portion between two rotating wheels, and concentric fluid admitting chambers in said intermediate portion communicating with the spaces between the wheels and the intermediate portion at equal radial distances from the turbine shaft. 100

4. In an elastic fluid turbine and in combination with a wheel of the radial flow type having on its face a plurality of buckets, a plurality of independent ducts for respectively leading working fluid to said buckets 110

at points located at different distances from the wheel center.

5. In an elastic fluid turbine and in combination with a wheel of the radial flow type having on its face a plurality of concentric rings of buckets, a plurality of independent ducts for respectively leading working fluid to different bucket rings.

6. The combination of a stationary compartment having guide blades on its face, a radial flow turbine wheel having on its face buckets coöperating with said guide blades, and in said compartment a plurality of independent passages for leading working fluid to said buckets at points located at different distances from the wheel center.

7. The combination of a stationary compartment having guide blades on its opposite faces, two radial flow turbine wheels having on their respective faces buckets coöperating with said guide blades, means in said compartment for balancing axial thrust of said wheels, and independent passages in said compartment for respectively leading working fluid to said buckets at points located at different distances from the wheel center. 20 25

In testimony whereof I have affixed my signature in presence of two witnesses.

GUSTAF DALÉN.
